UNITED STATES PATENT OFFICE.

AXEL A. T. STAHLÉ, OF CHICAGO, ILLINOIS.

HAIR-CUTTING TOOL.

1,286,823.

Specification of Letters Patent.

Patented Dec. 3, 1918.

Application filed December 1, 1917. Serial No. 204,851.

To all whom it may concern:

Be it known that I, AXEL AUGUST THEODORE STAHLÉ, a citizen of the United States, residing at Chicago, in the county of Cook and State of Illinois, have invented certain new and useful Improvements in Hair-Cutting Tools, of which the following is a specification.

This invention is a hair cutting tool employed in cutting the hair upon the head of a human being and is more particularly adapted for home or domestic use by an inexperienced person or one unskilled in the profession of barbering, wherein the cut hair will be of proper lengths without showing nicked or gouged places where the hair has been cut to a shorter length.

One object of the invention is to provide a tool having pivotally connected members including handles and with combs at one end of each of the members.

Another object is to provide a hair cutting tool that will include two pivotally mounted members each having combs at one end, making the mounting adjustable so that the combs may have their separation varied to determine the length of hair to remain, and employing a guide and spring serving to move and guide the members into engagement so that the combs are maintained in their adjusted positions.

Broadly stated the invention comprises a pair of members pivotally connected together, one end of each of said members being formed as a handle and at the opposite end provided with a comb, one of said members being slotted and in each of the slots pivotally mounted rods, one of which rods is provided with a series of holes longitudinally placed and the other rod being provided with a slidable collar having a rounded upper edge and a stationary collar adjacent the lower end of said rod with a spring placed between said collars and around the rod, the other of the members being provided with slots, one of which has a pin fastened transversely therethrough to engage with one of the holes of one of the rods, the other of said slots being adapted to have the other of said rods passed therethrough, said pin being removable so that the members may be spaced from each other at which time the spring serves to normally position the combs at the proper distance apart, and the rod serves as a guide to maintain the alinement.

One practical form of construction and assembly will be described and illustrated in the accompanying drawings, in which:

Figure 1 is a side elevation of the tool, 60

Fig. 2 is a top plan view of the tool, and

Fig. 3 is a sectional view on the line 3—3 of Fig. 1, and shows the assembly of the spring and guide rod with the two members.

In the preferred embodiment about to be described, the tool generally comprises two members 5 and 6 that are preferably formed of metal in order to provide strength and rigidity. Each of the members 5 and 6 are provided with curved ends forming the handles 7 and 8. These handles should be so curved that they will comfortably fit the human hand. The opposite end of the members 5 and 6 are provided with the combs 9 and 10. These combs may be secured to the members 5 and 6 in any approved manner such as indicated by the rivets 11 and 12.

The members 5 and 6 are preferably formed generally of square stock and their opposing surfaces adjacent the comb ends 80 may be beveled as indicated at 13 and 14. The opposite ends which form the handles 7 and 8 may be flattened and partake of an oval shape as indicated in Fig. 2. The member 6 is provided with slots 15 and 16 85 that pass clear through the member as shown more particularly in Fig. 1. The member 6 is provided with suitable holes that are in alinement transversely of the slots. These holes are adapted to receive the 90 pins 17 and 18.

The slots 15 and 16 are adapted to receive the rods 19 and 20. These rods are provided with suitable holes at their lower ends so that the pins 17 and 18 may be passed therethrough and form a pivotal mounting for the rods 19 and 20. The slots are of sufficient length to provide a longitudinal swinging of the rods. The rod 19 is provided with a series of holes 21. The member 5 is also provided with the slots 22 and 23. These slots are provided with curved end walls and through these slots the rods 19 and 20 are adapted to pass.

The holes 21 are adapted to be engaged 105 by a pin 24 that passes through alined holes formed in the member 5 and through the slot 22. This pin thus forms a pivotal mounting for the two members 5 and 6 and their relative distance apart may be varied 110 by removing the pin 24 and placing it in another of the holes 21.

The slot 23 is adapted to receive the rod 22 that is provided at its upper end with a hole 25 through which may pass a split or cotter pin. The rod 20 is provided adjacent the member 6 with a substantially stationary collar 26 and against the member 5 a movable collar 27 is placed. The end surface of the movable collar 27 is substantially flat while its upper surface is 10 rounded as indicated at 28.

A coil spring 29 encircles the rod 20 and is positioned so that its ends bear against the relatively stationary collar 26 and the flat surface of the collar 27. When the handles 7 and 8 are brought closer together 15 the spring 29 will be compressed between the collars 26 and 27. The rod 20 will then move within the slot 23 which is shaped to provide for the varying position.

To further provide for this positioning the rod 20 is pivotally mounted in the member 6. The spring 29 may be formed in any usual or customary way but is preferably formed of a suitable size of piano wire. 25 The collar 27 having the flat under surface 30 has its surface provided with a projecting flange indicated at 31 that is adapted to fit within and engage with the inner diameter of the spring 29. This flange will serve 35 to center and guide the spring 29 when compressing and expanding.

As shown in the several figures the rods 19 and 20 are formed of flat stock and these rods may be formed of any suitable material 35 and in any desired shape that will be best adapted to perform their several functions. As shown the rod 19 is somewhat shorter than the rod 20.

The comb 10 is adapted to rest against 40 the head of the person and the comb 9 engages with the hair and lifts it the proper distance away. Shears or other cutting tools are then employed to sever the hair. The amount of the separation between the 45 combs 9 and 10 will determine the length of hair remaining upon the head of the individual. Thus it will be seen that the hair may be cut to uniform lengths and that an inexperienced person may perform a good 50 job of hair cutting.

The tool may be adjusted for cutting different lengths by changing the position of the pin 24 with the hole 21 formed in the rod 19. The compressing or bringing together of the handles 7 and 8 will cause a 55 lifting action by the member 5 of the comb

9 so that the hair may be readily separated for cutting. The pin 24 may have a head in one end and adjacent the opposite end a hole that is adapted to receive a cotter 60 pin 32. Any other suitable means may be employed to permit the changing of the pin 24 to engage with the different holes 21.

What I claim is:

1. A hair cutting tool comprising a member having a comb at one end and a handle at the opposite end, a bar pivotally connected to the member intermediate its ends and provided with a plurality of vertically spaced openings, a second member provided on one end with a comb and on the opposite end with a handle, said second member pivotally and adjustably connected to the bar, and a guide bar pivotally connected to the first member and passing through the opening in the second member.

2. A hair cutting tool comprising a pair of pivotally mounted members, including handles, a comb upon one end of each of the members, a guide rod pivotally mounted 80 upon one of the members, a coil spring in the rod, the ends of the spring being in engagement with the members, one of said members having a slot through which the rod is adapted to pass and projects beyond, 85 said pivotal mounting including a rod connected to one of the members and having a series of holes longitudinally spaced, the other of said members being provided with a slot through which passes said latter rod, 90 and with a hole transversely positioned so that a pin may be passed through it and one of the holes in the rod to provide for adjustment of the members and the combs.

3. A hair cutting tool comprising a pair 95 of handled and slotted members pivotally connected together, said connection also affording an adjustment between the members, a guide rod pivotally connected to one of the members and passing a slot in the 100 opposing member, a plurality of collars on said rod, a coiled spring on said rod and between the collars, and a comb transversely mounted on and carried at one end of each of the members, said spring normally acting 105 to move the combs toward each other.

In testimony whereof I affix my signature in presence of two witnesses:

AXEL A. T. STAHLÉ.

Witnesses:

EDWARD SWONBORG,
CARL JOHNSON.
